UNITED STATES PATENT OFFICE.

JOSEPH W. THOMPSON, OF SALEM, OHIO, ASSIGNOR TO HENRY WATERS
HARTMAN, TRUSTEE.

DESIGN FOR A RIVETER MEMBER.

SPECIFICATION forming part of Design No. 31,139, dated July 4, 1899.

Application filed April 10, 1899. Serial No. 712,543. Term of patent 14 years.

To all whom it may concern:

Be it known that I, JOSEPH W. THOMPSON, mechanical engineer, residing at Salem, in the county of Columbiana and State of Ohio, have 5 invented and produced a new and original Design, Shape, or Configuration for a Riveter Member, of which the following is a specification, referring to the accompanying drawing, which forms a part of this specification.

10 The figure shows inside elevation my design as embodied in the riveter member to which it relates.

The riveter-head H is formed in upright U shape, as shown, one leg of the U having a rivet-setting point in the position shown and 15 the other leg of the U having a shank or extension S shaped as a carrier, as shown in the drawing, and partly screw-threaded. Be-

yond the screw-threads the shank turns downward in shape and in position relatively to 20 the U-shaped head to terminate at R in the same horizontal plane with the bottom of the U-shaped head H. The portion G of the shank is shaped to be conveniently grasped by the hand of the user.

I claim and desire to secure by Letters Patent the following:

The design for a riveter member as shown and described.

In testimony whereof I have hereunto set 30 my hand, at Salem, Ohio, this 18th day of April, 1898.

JOSEPH W. THOMPSON.
